GEORGE A. BURNHAM, OF SAUGUS, MASSACHUSETTS, ASSIGNOR TO S. B. CONDIT, JR., OF BOSTON, MASSACHUSETTS.

SELECTIVE TIME-LIMIT CONTROLLING DEVICE FOR ELECTRIC SWITCHES.

1,288,502.

Specification of Letters Patent.

Patented Dec. 24, 1918.

Application filed July 21, 1911, Serial No. 639,763. Renewed May 11, 1918. Serial No. 234,015.

To all whom it may concern:

Be it known that I, GEORGE A. BURNHAM, a citizen of the United States, residing at Saugus, in the county of Essex and State of Massachusetts, have invented an Improvement in Selective Time-Limit Controlling Devices for Electric Switches, of which the following is a specification.

This invention relates to time-limit controlling-devices for electric-switches. Heretofore time-limit controlling-devices for electric-switches have been devised including operating-means for the switch requiring a prolonged period of time to operate the switch. In some instances, the time-controlled element of the operating-means is moved at a constant speed through a definite interval of space, hence, the period of time consumed by it is the same regardless of the strength of the overload. In other instances the time-controlled element is moved at a varying speed according to the strength of the overload, so that the period of time consumed by it varies according to the strength of the overload, being less on a heavy overload than on a light overload. Furthermore, the operating-means for the switch has been made manually adjustable so that the time-controlled element is moved through an interval of space of greater or less length in operating the switch. So far as I am aware, all of these controlling-devices made by others have failed to be selective in action, notwithstanding their different normal settings, upon the occurrence of a very heavy overload, as, in such case, they will all operate their respective switches simultaneously or substantially so and unnecessarily open the circuits.

This invention has for its object the construction of a time-limit controlling-device for electric-switches having operating-means for the switch which requires a prolonged period of time to operate the switch, but which is adjustable automatically to vary said period of time according to the strength of the overload. My present invention is applicable to either type of controlling-device above referred to, and for purposes of illustration both forms of controlling-devices are here shown, one wherein the time-controlled element is controlled by the overload current and moved at a constant speed, and the other wherein the time-controlled element is controlled by the overload current

and moved at a speed dependent upon the strength of the overload, up to a predetermined current value, and on overloads of higher current values is moved at a constant speed regardless of the strength of the overload, so that in any event a prolonged period of time is maintained. For preference I also select a type wherein the operating-means is manually adjustable to vary the period of time consumed by it in operating the switch, so that each time-limit controlling-device may have a different normal setting from others which are arranged in the circuit.

In the present embodiment of my invention automatic variation of the operating means is accomplished by varying the length of the interval of space through which the time-controlled element moves, by means controlled by the overload current, but my invention is not limited to accomplishing this result in this manner, as I desire to include within the spirit and scope of my invention any means to automatically adjust said operating-means to vary the time consumed by it in completing its operation to operate the switch, which is controlled by the overload current, and, especially when said operating-means is also actuated by the overload current.

In the present embodiment of my invention the operating-means comprises a controller for the switch and an operating-device for said controller, and said controller comprises an electro-magnet to operate the switch, and the operating-device comprises a circuit-closer for the circuit of said electro-magnet, both members of said circuit-closer being movable toward and from the other, movement of one member being automatically controlled by the overload current to vary its position with respect to the other member, to reduce the interval of space and correspondingly reduce the time required for the members to engage and close the circuit of the controller to operate the switch, while the other member is operated by an electric-motor, controlled by the overload, at a constant or variable speed according to the construction of the motor, or according to the current-value of the overload.

Figure 1 is a side elevation of a time-limit controlling-device for electric-switches, embodying this invention.

Fig. 2 is a left-hand end elevation of the same.

Fig. 3 is a plan view of the operating-device for the switch-controller.

5 Fig. 4 is a detail of the operating-means for the switch and a diagram of an electric-motor and circuit which may be employed.

10 Fig. 5 is a detail of the operating-means for the switch and a diagram of a modified 15 form of electric-motor and circuit which may be employed.

15 Referring to Fig. 4, wherein a single line-circuit is shown as a simple manner of illustrating my invention, 20 represents the circuit or line wire, and 21, a switch of any suitable construction, but preferably of a type adapted to be operated automatically to open the circuit, and manually to close the same. A snap-switch of usual construction 20 is here shown, having a hand-lever 22, and an actuating-spring 23. This is the switch which the time-limit controlling-device forming the subject-matter of this application is designed to operate automatically, to open the circuit 20. The time-limit controlling-device involves operating-means for the switch and means responsive to an overload current to actuate it, or to control its operation, and means also responsive to 25 the overload current to adjust it whereby the period of time required for it to operate the switch is reduced according to the strength of the current. As here shown for the purpose of illustrating my invention 30 said operating-means comprises a switch-controller of the electrical type, which is adapted, when operated, to open the switch, and an operating-device for the circuit of said switch-controller, which requires a pro- 35 longed period of time to complete its operation to operate the switch-controller, and said operating-device is automatically adjusted by means responsive to the overload current, and is also actuated by means re- 40 sponsive to the overload current.

45 The switch-controller here shown consists of an electro-magnet 24, connected in a battery circuit 25, the armature of which is connected to a lever 28, secured to a pivot-shaft, and to said shaft is secured a short arm 29, which is designed to engage and operate a snap-switch to open the circuit 20, upon energization of the magnet.

50 The operating-device for the switch-controller, as here shown, consists of a circuit controlling-device for the circuit 25, said circuit controlling-device comprising two members, both of which are movable toward and from each other, and one of them is 55 time-controlled, so as to require a prolonged period of time to move and engage the other member. One of said circuit-closing members comprises two circuit-contacts 26, 27, adapted to be connected with the circuit 25, and said contacts are arranged on an arm-

30, of insulating material, secured to a pivot-shaft 31, bearing a pinion 32, which is in mesh with a toothed-sector 33, pivoted at 34, and connected by a link 35, with the armature of a solenoid 75, which armature 70 is shown in Fig. 1 as in its normal elevated position, and in Fig. 4 as moved downward in response to the pull of the winding of the solenoid. Said solenoid is included in a circuit 70, of the secondary-coil 71, of a 75 transformer, the primary-coil 72, of which is included in the circuit 20, so that said solenoid is responsive to an overload upon the circuit 20, which is reduced by or through a transformer. Said solenoid constitutes the means which is responsive to an overload current and which is employed to adjust the operating-means for the switch, by moving the circuit-closing member 26, 27, so as to vary its distance from the 80 co-operating circuit-closing member, according to the movement of the armature of the solenoid. On a light overload said circuit-closing member 26, 27, will be moved counter-clockwise a short distance, as shown in 85 Fig. 4, and on a heavy overload, will be moved a correspondingly greater distance, although it will be understood that movement of the core of the solenoid is checked when it arrives at or about the middle of 90 the winding of the solenoid. The co-operating circuit-closing member of the circuit-closing device is time-controlled and consists of a yoke or arm 40, arranged to be moved rotarily in a vertical plane, having 100 at its extremity a cross-piece or pin 41, which, when the yoke or arm arrives at the end of its rotary movement is adapted to engage the circuit-contacts 26, 27, to thereby close the circuit 25 of the switch-controller. 105 Said yoke or arm is mounted loosely on a shaft 42, to which a worm-wheel 43, is secured, and means, as a screw 44, is provided for adjustably connecting said yoke or arm with said worm-wheel in different radial 110 positions, said screw entering any one of a series of holes 45, arranged in the side of said worm-wheel, so that the yoke or arm will be moved by said worm-wheel. Said worm-wheel also has a pin 46, projecting 115 from its side which is adapted to engage a stop, here shown as a part of the field-frame of an electro-magnet, to thus determine its normal position or starting point, and said worm-wheel normally occupies this position 120 regardless of the position of the yoke or arm relative thereto. As the worm-wheel is revolved in the direction of the arrow Fig. 1, said yoke or arm is moved by it through an interval of space, which is variable in length 125 according to its connection with the worm-wheel to engage the circuit-contacts 26, 27, and the relative position of the contacts 26, 27.

130 The movement of the worm-wheel and

yoke or arm to close the circuit 25, of the switch requires a prolonged period of time and such movement is controlled by means responsive to the overload, so that said circuit-closing member is controlled by the overload current.

As a means to move the worm-wheel and the yoke or arm an electric-motor is employed.

10 In Figs. 1 to 4 inclusive, the electric-motor is constructed and arranged substantially the same as shown in my Letters Patent No. 1,041,716, dated October 15, 1912, it being of the series type or having the general characteristics of a series motor, and constructed and arranged in such manner that its magnetic-circuit and windings are so proportioned as to require an overload of approximately three times the full load of 20 the circuit controlled by the switch to cause the motor-armature to attain its speed-limit, although a lesser overload will cause the motor-armature to revolve at a slower speed proportionate to the strength of the over- 25 load, and a greater overload, meaning an overload in excess of that required to cause the motor-armature to attain its speed-limit will cause the motor-armature to revolve at its maximum speed regardless of the 30 strength of the overload. Said electric-motor is included in a transformer circuit 70, so as to be responsive to the overload, being controlled and operated by it.

In Fig. 5 I have shown an ordinary constant speed motor connected in a battery circuit, which is controlled by the overload current but operated by the battery current. So far as my present invention is concerned, either type may be employed or any other 40 suitable type, as the variation in the prolonged period of time consumed by the timed-element of the operating-means is automatically controlled by means independent of the motor and is operated or controlled by the overload.

Referring to Figs. 1 to 4, 48 represents the armature of the motor, which is supported in suitable bearings, and one end of the shaft of the armature is extended as at 50 49, and is threaded to form a worm. The worm-wheel 43 is arranged beneath said worm, but is normally out of engagement therewith, and is supported by a movable member whereby it is movable into and out 55 of engagement with said worm. Said worm serves as the means to drive the worm-wheel, and therefore, constitutes the actuator for the operating-device. The engagement of the operating-device with its actuator is controlled by the current which operates the motor, and herein said worm-wheel 43, is supported by an extension of the lower part of the field-frame of the motor, which is made movable with respect to the upper part 60 thereof, whereby the worm-wheel is moved

into and out of engagement with its actuator. The field-frame of the motor is or may be made in two parts, or may have a movable part in connection with it, and, as here shown, said frame is divided on a horizontal line, 50 representing the upper part and 51 the lower part, and said parts are hingedly connected together at 52, so that the lower part is movable toward and from the upper part, and the upper part is held stationarily by being connected to the support 53. With the exception of making the field-frame in two parts it may be constructed, generally speaking, in any well-known or suitable manner, to support the field-coils. Movement of the lower part 51 in a direction away from the upper part is limited by an adjustable yielding stop comprising, as shown in Fig. 1, a pin 55, extended through an ear 56, arranged thereon, which engages a spring 57, resting against a fixed abutment 58, which may be a downward extension of the upper part. The lower end of the ear 56 has a hole through it for a bar 60, which is horizontally arranged and secured to the extension 58, and which projects through said hole for a considerable distance, and a spring 59 is arranged on said bar between the ear and a nut 61, adjustably connected with the bar, which exerts its pressure upon the ear in a direction to move the lower part of the frame downwardly, and upward movement of the frame acts to compress said spring so that such movement is resisted by the spring, and by adjustment of the spring greater or less force may be required to lift the frame. The bar 60 may be calibrated, if desired, to indicate in amperes the force required to lift the frame by the magnetic influence, due to the current traversing the field-coils of the motor, and the motor to act as a magnet. Thus the spring 59 not only acts as a retractile spring to assist gravity in moving the part 51 away from the part 50, but also may be employed to determine the energy required to lift it, and hence serves as an adjusting-device for the motor, whereby it may be caused to move the operating-device into engagement with its actuator upon an overload of a given value, or in excess of said value. When the lower part of the field-frame is in its lowermost position, being removed from or remote from the upper part, as represented in Fig. 1, said worm-wheel is removed from engagement with the worm, and when said lower part of the field-frame is in its uppermost position, as represented in Fig. 3, said worm-wheel is in engagement with the worm. The motor is or may be arranged in the transformer circuit 70, but, is normally short-circuited by a switch or circuit closer, the fixed members 73, of which are engaged by a plate 74, connected with the 130

armature of the solenoid 75. When said solenoid pulls down its armature due to an overload on the circuit 20, the circuit-closer 73, 74, will be operated to open the short-circuit of the motor, as shown in Fig. 4, so that the motor will be operated by the overload current through the transformer; and the lower part of the field-frame will be attracted toward the upper part thereof to move the operating-device for the switch-controller into engagement with its actuator; and the arm 40 will be moved rotarily clockwise toward and into engagement with the circuit-contacts 26, 27, to cause the switch controller to operate the switch and open the circuit 20. In case the overload current passes over the circuit for a short period of time and then ceases, and such period of time is insufficient to move the operating-device far enough to cause its arm 40 to engage the circuit-contacts 26, 27, then as soon as said overload ceases the parts will be restored to normal by gravity. The distance which the arm 40 moves depends upon the position of the circuit-contacts 26, 27, with respect thereto, and the position of said contacts is controlled by the overload through the solenoid 75, to thus control the length of the period of time. By controlling the length of the prolonged period of time required for the operating-means to operate the switch by means operated by the overload is of the greatest importance, as it enables a set of time-limit controlling-devices to be selective regardless of the strength of the overload.

By the means shown in Figs. 1 to 4, the variation in the period of time occurs at both ends thereof, as for instance, the movement of the arm 40 is variable according to the current value of the overload up to a predetermined current value, and is definite on overloads of higher current values, and the distance said arm moves is variable according to the position of the arm 30 bearing the contacts 26, 27, and movement of said arm 30 is variable according to the current value of the overload up to a predetermined current value, and is definite on overloads of higher current values. The relatively stationary contact-member 30 will only approach the retarded contact-member 40 a limited distance, so that in any event with a given setting of each relay, there will be a certain period of time elapse between the occurrence of the overload and the tripping of the circuit-breaker, which will be constant for each relay above certain values of overload, and no matter how much higher the overload may be, and also different for each relay in the system according to its setting. This result will be obtained also by the form of apparatus shown in Fig. 5, and with either form of apparatus the chart lines will be indicated by inverse

curves followed by straight lines, which will not intersect on a heavy overload, as for instance, on an overload in excess of three times the full load of the current which is controlled by the switch. The form of apparatus shown in Figs. 1 to 4 has the advantage over the form shown in my patent aforesaid of providing a very short movement for the contact-member 40, upon the occurrence of a very heavy overload, so that a very short period of time is consumed, although such period of time is of a substantial, yet of definite length, while with the motor of the patent, said contact-member 40 moves through the same arc on both heavy and light overloads, its speed of movement being greatly accelerated on heavy overloads thus the motor in the present form of apparatus need not have as wide a range of flexibility.

Referring to Fig. 5, the electric-motor may be constructed the same as the motor shown in Figs. 1 and 2, with the exception that its magnetic-circuit and windings are proportioned as usual in electric-motors, so that it is arranged to be operated at a constant speed by a battery current or other source of energy. In said Fig. 5, the electric-motor is arranged in a battery-circuit 90, which is closed by the circuit-closing members 73, 74, controlled by the solenoid 75, so that upon the occurrence of an overload, said battery-circuit is closed and the motor is caused to operate at a constant speed to move the arm 40 clockwise at a constant speed, but the distance said arm moves is varied by means controlled by the solenoid 75, which means together with the solenoid are substantially the same as shown in Fig. 4, so that the same result is obtained, although the variation in the prolonged period of time occurs at only one end of the period, said variation being produced by the action of the solenoid in response of an overload. The constant speed-motor, being included in a battery-circuit or driven by an independent source of electric energy, might itself act as a definite time-limit relay, but, as here shown, it will not operate the switch-operating means except in conjunction with the solenoid 75, by which the time of operation is varied according to the current value of the overload up to an overload of a predetermined current value, and by which the time of operation will be definite on overloads of higher current values. Hence, in the form of apparatus shown in Fig. 5, the chart lines will be indicated by inverse curves of a pitch slightly differing from that of the aforesaid apparatus, and then by straight lines which will not intersect on heavy overloads. In said Fig. 5, the plate 74, normally occupies a position above the contacts 73, and will be moved downward into engagement with said contacts upon a

downward movement of the core of the solenoid, and in view of the fact that engagement is required upon the occurrence of a light, as well as a heavy overload, said 5 plate is loosely arranged on the stem connected with the core of the solenoid, and is held by a spring, so that movement of the core of the solenoid independently of the plate is permitted upon the occurrence of 10 heavy overloads, while the plate is engaging the contacts 73. Upon the occurrence of a light overload, the core will be moved a short distance sufficient to cause the plate 74 to engage the contacts 73, and the arm 30, to be 15 moved counter-clockwise a short distance only, as represented in Fig. 5, and upon the occurrence of a heavy overload, the core of the solenoid will be moved farther, but the plate 74 will still engage said contacts and 20 will there remain while the core moves independently of it; although downward movement of the core is limited, as here shown, when it arrives at or about the middle of the solenoid, and will not be moved farther, regardless of the strength of the overload. 25 This form of apparatus, shown in Fig. 5, wherein a constant speed actuator is employed for one of the contact-members, and a variable actuator employed for the other 30 contact-member, which variable actuator is arranged to be controlled by an overload current in the manner herein set forth, forms the subject matter of a divisional application No. 873,062, filed November 19, 1914.

35 In lieu of employing an electric-motor to operate the operating-means for a switch, any other suitable device may be employed, which is controlled by an overload current, and is arranged to operate said operating- 40 means at a variable or constant speed or both.

I claim:

1. In a selective time-limit controlling-device for electric-switches, the combination 45 of switch operating-means requiring a prolonged period of time to operate the switch, including coöperating contact-members, means controlled by an overload current to adjust one of said members to reduce said 50 period of time according to the strength of the overload, and means controlled by the overload current to actuate the other member at a variable speed according to the strength of the overload, substantially as described.

2. In a selective time-limit controlling-device for electric-switches, the combination of switch operating-means requiring a prolonged period of time to operate the switch, 60 including coöperating contact-members, means controlled by an overload current to adjust one of said members to reduce said period of time according to the strength of the overload, and means controlled by the 65 overload current to actuate the other mem-

ber at a variable speed according to the current value of the overload up to a predetermined current value and at a definite speed on overload of higher current values; substantially as described. 70

3. In a selective time-limit controlling-device for electric-switches, the combination of switch operating-means requiring a prolonged period of time to operate the switch, including coöperating contact-members, 75 means controlled by an overload current to adjust one of said members to reduce said period of time according to the strength of the overload, and an electric-motor controlled by the overload current to actuate 80 the other member at a variable speed according to the strength of the overload, substantially as described.

4. In a selective time-limit controlling-device for electric-switches, the combination 85 of switch operating-means requiring a prolonged period of time to operate the switch, including coöperating contact-members, means controlled by an overload current to adjust one of said members to reduce said 90 period of time according to the strength of the overload, and an electric-motor controlled by the overload current which is constructed and arranged to actuate the other member at a variable speed according to the 95 current value of the overload up to a predetermined current value and at a definite speed regardless of the strength of the overload on higher current values, substantially as described. 100

5. In a selective time-limit controlling-device for electric-switches, the combination of switch-operating-means requiring a prolonged period of time to operate the switch, including coöperating contact-members, 105 means controlled by an overload current to adjust one of said members to reduce said period of time according to the strength of the overload, and means controlled by the overload current to actuate the other member at a variable speed according to the strength of the overload, both members being permitted to return to normal immediately upon cessation of the overload, substantially as described. 110

6. A selective time-limit controlling-device for electric-switches including a controller for the switch, an operating-device for said controller comprising two members, one of which is time-controlled, means controlled by an overload current to actuate said time-controlled member at a variable speed according to the strength of the overload, and means controlled by the overload current to move the other member toward 120 the time-controlled member, substantially as described. 125

7. A selective time-limit controlling-device for electric-switches including a controller for the switch, an operating-device 130

- for said controller comprising two members, one of which is time-controlled, means controlled by an overload current to actuate the time-controlled member at a variable speed 5 up to a predetermined current value and at a definite speed on higher current values, and means controlled by the overload current to move the other member toward the time-controlled member, substantially as described.
8. A selective time-limit controlling-device for electric-switches including a controller for the switch, an operating-device for said controller comprising two members, 15 one of which is time-controlled, an electric-motor controlled by the overload current to actuate said time-controlled member, and means controlled by the overload current to move the other member toward the time-controlled member, substantially as described.
9. A selective time-limit controlling-device for electric-switches including a controller for the switch, an operating-device 25 for said controller comprising two members, one of which is time-controlled, an actuator into and out of engagement with which said time-controlled member is movable, means controlled by the overload current to move 30 said time-controlled member into and out of engagement with its actuator, means controlled by the overload current to drive said actuator, and means controlled by the overload current to move the other member 35 toward the time-controlled member, substantially as described.
10. A selective time-limit controlling-device for electric-switches including a controller for the switch, an operating-device 40 for said controller comprising two members, one of which is time-controlled, an actuator into and out of engagement with which said time-controlled member is movable, means controlled by the overload current 45 to move said time-controlled member into and out of engagement with its actuator, and an electric-motor controlled by the overload current to drive said actuator, and means controlled by an overload current to 50 move the other member toward the time-controlled member, substantially as described.
11. A selective time-limit controlling-device for electric-switches including a controller for the switch, an operating-device 55 for said controller comprising two members, one of which is time-controlled, means controlled by an overload current to move one of said members toward the other to reduce the time required for the time-controlled member to complete its operation, means to adjust one of the members to vary the length of said period of time, and means controlled by an overload current to actuate the time-controlled member, substantially as described.
12. A selective time-limit controlling-device for electric-switches including an electro-magnetic controller for the switch, a circuit-closing device for the circuit of said controller comprising two members, one of which is time-controlled, means controlled by an overload current to move one of said members toward the other to reduce the time required for the members to engage, and means controlled by the overload current to move the time-controlled member, substantially as described.
13. A selective time-limit controlling-device for electric-switches including an electro-magnetic controller for the switch, a circuit-closing device for the circuit of said controller comprising two members, one of which is time-controlled, means controlled by an overload current to move one of said members toward the other to reduce the time required for the members to engage, means to adjust one of the members to vary the length of said period of time, and means controlled by the overload current to move said time-controlled member, substantially as described.
14. A selective time-limit controlling-device for electric-switches including an electro-magnetic controller for the switch, a circuit-closing device for the circuit of said controller, a solenoid responsive to an overload to move one member of said circuit-closing device toward the other member, and means controlled by the overload current to move said other member toward the first named member to close the circuit, substantially as described.
15. A selective time-limit controlling-device for electric-switches including a controller for the switch, a circuit-closing device for the circuit of said controller, a solenoid responsive to an overload to move one member of said circuit-closing device toward the other, and an electric-motor responsive to the overload to move the other member toward the first named member to close the circuit, substantially as described.
16. A selective time-limit controlling-device for electric-switches including a controller for the switch, a circuit-closing device for the circuit of said controller, a solenoid responsive to an overload to move one member of said circuit-closing device toward the other, and an electric-motor responsive to the overload to move the other member toward the first named member to close the circuit at a speed dependent upon the strength of the overload, substantially as described.
17. A selective time-limit controlling-device for electric-switches including an electro-magnetic controller for the switch, a cir-

- cuit-closing device for the circuit of said controller, means responsive to an overload to move one member of said circuit-closing device toward the other member to reduce 5 the time required for the members to engage, an actuator for the other member into and out of engagement with which it is movable, means controlled by the overload to move said other member into engagement 10 with its actuator, and an electric-motor to drive said actuator, substantially as described.
18. In a selective time-limit controlling-device for electric-switches, the combination 15 of switch operating-means including movable contact-members, one of which is time controlled, means controlled by an overload current arranged to actuate the time-controlled member at a speed proportional to 20 the current value of the overload up to a predetermined current value and at a definite speed on overloads of higher current values, and means controlled by the overload current to move the other member toward the 25 time-controlled member varying distances according to the current value of the overload up to a predetermined current value, and definite distances on overloads of higher current values, substantially as described.
19. In a time-limit controlling-device for 30 electric-switches, the combination of switch operating-means including movable contact-members, one of which is time-controlled, and means responsive to and controlled by 35 an overload current to move the other member toward the time-controlled member a variable distance according to the current value of the overload up to a predetermined current value, and a definite distance on 40 overloads of all higher current values, and means to move the time-controlled member into engagement with the other member in any position it may occupy, providing overload condition continues, substantially as de- 45 scribed.
20. In a time-limit controlling-device for electric-switches, the combination of switch operating-means, time-controlled means associated therewith including two contact 50 members, a solenoid also associated with said switch operating means, the core-piece of which is movable in response to an overload a variable distance according to the strength of the overload, up to a predetermined 55 current value, and is movable its maximum distance on all overloads of higher current values to correspondingly move one of the contact members, and means to move the other contact-member into engagement with the aforesaid contact-member 60 in any position it may occupy, upon the continuance of abnormal conditions, substantially as described.
21. The combination with an electrical in- 65 stallation, of a relay comprising a movable member, means whereby said member is moved at a speed which varies as a direct function of the rate of flow of current in said installation, and means coöperating with said movable member for interrupting 70 the flow of current in said installation when said member has moved from an initial position a distance which is an inverse measure of the rate of flow of current in said in- 75 stallation.
22. The combination with an electrical in- 75 stallation, of a relay comprising a movable member, means whereby said member is moved at a speed which varies as a direct function of the rate of flow of current in 80 said installation, a second movable member arranged to move toward and in the path of movement of said first mentioned movable member, means for moving said second member toward said first mentioned member a 85 distance which is a direct function of the rate of flow of current in said installation, and means controlled by the engagement of said members for interrupting the flow of current in said installation. 90
23. The combination with an electrical in- 90 stallation, of a relay comprising a movable member, means adapted to move said member at a speed which varies as a direct function of the rate of flow of current in said in- 95 stallation, means for causing said last mentioned means to move said member when the rate of flow of current in said installation exceeds a predetermined amount, and means coöperating with said movable member for 100 interrupting the flow of current in said installation when said member has moved a distance which is an inverse measure of the rate of flow of current in said installation. 100
24. The combination with an electrical in- 105 stallation, of a relay comprising a movable member, means adapted to move said member at a speed which varies as a direct function of the rate of flow of current in said in- 110 stallation, means for causing said last mentioned means to move said member when the rate of flow of current in said installation exceeds a predetermined amount, a sec- 115 ond movable member arranged in the path of movement of said first mentioned mem- 115 ber, means for moving said second member toward said first mentioned member a distance which is a function of the rate of flow of current, and means controlled by the engagement of said members for interrupting the flow of current in said installation. 120
25. The combination with an electrical in- 120 stallation, of a relay comprising a movable member having an initial position, means adapted to move said member at a speed 125 which varies as a direct function of the rate of flow of current in said installation, means for causing said last mentioned means to

- move said member when the rate of flow of current in said installation exceeds a predetermined amount, means adapted to return said movable member to its initial position when the rate of flow of current is less than said predetermined amount, and means coöperating with said movable member for interrupting the flow of current in said installation when said member has moved a distance which is an inverse measure of the rate of flow of current.
26. The combination with an electrical installation, of a relay comprising an electric circuit, a movable contact in said circuit, means adapted to move said contact at a speed which varies as a direct function of the rate of flow of current in said installation, means for causing said last mentioned means to move said member when the rate of flow of current in said installation exceeds a predetermined amount, a second movable contact in said circuit arranged in the path of movement of said first mentioned contact, means for moving said second contact toward said first mentioned contact a distance which is a function of the rate of flow of current, and means controlled by the engagement of said contacts for interrupting the flow of current in said installation.
27. The combination with an electrical installation, of a relay comprising electromagnetic means electrically connected to the installation and adapted to produce a magnetic field proportional to the rate of flow of current in said installation, an armature rotatably mounted in said magnetic field, a movable member adapted to be operatively connected to said armature when the rate of flow of current in the installation exceeds a predetermined amount, and means coöperating with said movable member for interrupting the flow of current in said installation when said member has moved a distance which is an inverse measure of the instantaneous rate of flow of current.
28. In combination with an electrical installation, of a relay comprising electromagnetic means electrically connected to the installation and adapted to produce a magnetic field proportional to the rate of flow of current in said installation, an armature rotatably mounted in said magnetic field, a movable member adapted to be operatively connected to said armature when the rate of flow of current in the installation exceeds a predetermined amount, means adapted to return said movable member to its initial position when the rate of flow of current is less than said predetermined amount, and means coöperating with said movable member for interrupting the flow of current in said installation when said member has moved a distance which is an inverse measure of the rate of flow of current.
29. The combination with an electrical installation, of a relay comprising two coöperating movable members, means for moving one of said members toward the other member at a speed which is a direct function of an electrical characteristic of the installation, means for moving the other member toward its coöperating member a distance which is a function of an electrical characteristic of the installation, and means controlled by the engagement of said members for interrupting the flow of current in said installation.
30. A relay comprising in combination an electric circuit, two movable circuit closing contacts included in said circuit, means for moving one of said contacts toward the other contact at a speed which varies as a function of an electrical characteristic of an electrical installation, and means for moving the other contact toward its coöperating contact a distance which is a function of an electrical characteristic of the installation.
- In testimony whereof, I have signed my name to this specification, in the presence of two subscribing witnesses.

GEORGE A. BURNHAM.
